CLAIM

The ornamental design for a surface configuration of a rear fender for a vehicle, as shown and described.

DESCRIPTION

This application is related to the following co-pending applications, of the inventor, filed on even date herewith: Application Ser. No. 29/151,801, entitled “Surface Configuration of a Vehicle and Toy”; and Application Ser. No. 29/151,814, entitled “Surface Configuration of a Side of a Vehicle”.

FIG. 1 is a front view of a first embodiment of a surface configuration of a rear fender for a vehicle according to my novel design;

FIG. 2 is a perspective view of the first embodiment of the surface configuration of a rear fender for a vehicle according to my novel design;

FIG. 3 is a front view of a second embodiment of the surface configuration of a rear fender for a vehicle according to my novel design; and,

FIG. 4 is a perspective view of the second embodiment of the surface configuration of a rear fender for a vehicle according to my novel design.

The broken lines included in the drawings depict environment and are not part of the claimed design.
